(57) **CLAIM**

The ornamental design for an animal hair removal brush, as shown and described.

DESCRIPTION

FIG. 1 is a first perspective view of an animal hair removal brush showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is another perspective view, but shown in an open position of use for clarity of illustration.

The broken lines shown in the drawings depict portions of the animal hair removal brush in which the design is embodied that form no part of the claimed design.
